CLAIM

The ornamental design for a position lamp for watercraft, as shown and described.

DESCRIPTION

This application contains at least one drawing executed in color.

FIG. 1 is a front elevational view of a position lamp for watercraft showing my new design, with the lamp body extended from its housing;

FIG. 2 is a right side elevational view thereof;

FIG. 3 is a bottom, side perspective view thereof;

FIG. 4 is a top view thereof;

FIG. 5 is a rear view thereof;

FIG. 6 is a front perspective view of the position lamp for watercraft showing my new design, with the lamp body retracted in its housing;

FIG. 7 is a side elevational view thereof with the lamp body retracted;

FIG. 8 is a rear view thereof with the lamp body retracted; and,

FIG. 9 is a top view thereof with the lamp body retracted.
